UNITED STATES PATENT OFFICE.

JOHN E. KALGREN, OF MINNEAPOLIS, MINNESOTA, ASSIGNOR TO J. R. CLARK COMPANY, OF MINNEAPOLIS, MINNESOTA, A CORPORATION OF MINNESOTA.

EXTENSION-LADDER-ASSEMBLING MACHINE.

Application filed July 14, 1927. Serial No. 205,828.

My invention has for its object to provide a highly efficient extension ladder assembling machine, and to this end it consists of the novel devices and combinations of devices 5 hereinafter described and defined in the claims.

In the accompanying drawings, which illustrate the invention, like characters indicate like parts throughout the several views.

10 Referring to the drawings:

Figs. 1 and 2 are views in side elevation showing the head and rear sections of the machine, respectively;

15 Figs. 3, 4 and 5 are fragmentary plan views showing the rear, intermediate and head sections of the machine, respectively;

Fig. 6 is a view partly in end elevation and partly in transverse vertical section taken on the irregular line 6—6 of Fig. 2, on an enlarged scale;

Fig. 7 is a view partly in elevation and partly in transverse vertical section taken on the line 7—7 of Fig. 1, on an enlarged scale;

20 Fig. 8 is a view partly in rear end elevation and partly in transverse vertical section taken on the line 8—8 of Fig. 2, on an enlarged scale, some parts being broken away and other parts shown by means of broken lines;

25 Fig. 9 is a fragmentary plan view of the cross-heads and eccentric connections shown in Fig. 8 at the head section of the machine;

Fig. 10 is fragmentary side elevation of the machine at the head section as shown in Fig. 35 1, on an enlarged scale:

Fig. 11 is a fragmentary detail view with some parts sectioned on the line 11—11 of Fig. 4, on an enlarged scale;

30 Fig. 12 is a fragmentary detail view with some parts sectioned on the line 12—12 of Fig. 4;

Fig. 13 is a plan view showing the manual control for the centering jaws and the automatic clutch release mechanism;

45 Fig. 14 is a detail view with some parts sectioned on the line 14—14 of Fig. 13;

Fig. 15 is a detail view with some parts sectioned on the line 15—15 of Fig. 13;

50 Fig. 16 is a view principally in diagram showing the right-hand pair of jaws as shown in Fig. 8, released;

Fig. 17 is a fragmentary plan view of one of the squeezing abutments;

Figs. 18, 19 and 20 are plan views showing

different types of ladder sections assembled 55 on the machine;

Fig. 21 is a detail view with some parts sectioned on the line 21—21 of Fig. 18, on an enlarged scale;

Fig. 22 is a view of the ladder shown in 60 Fig. 5, with some parts sectioned on the line 22—22 of said figure; and

Fig. 23 is a view of the ladder shown in Fig. 3, with some parts sectioned on the line 65 23—23 of said figure.

The frame of the machine includes heavy cast head, rear, and intermediate pedestals 23, 24 and 25, respectively, rigidly connected at their bases by a central longitudinally extended I-beam 26 and at their top portions 70 by a pair of laterally spaced side longitudinally extended I-beams 27. Said frame further includes heavy cast skeleton cross tie members 28 and 29 supported on the I-beams 27 and rigidly connect the same. As shown, 75 there are two cross tie members 29 and they are substantially like the cross tie members 28 with the exception that they have depending gear cases 30 formed therewith midway between the I-beams 27. Each cross tie member 28—29 has formed therewith, at its end portions, ways 31 on which a pair of cross-heads 32 are slidably mounted for movement toward or from each other, transversely of the machine.

85 The crossheads 32 on each side of the machine are rigidly connected for common sliding movement by a longitudinally extended sill 33 in the form of an inverted channel beam. Reverse movements are imparted to the crossheads 32 on opposite sides of the machine by an eccentric shaft 34 journaled in bearings in the cross tie members 28 and the gear cases 30. Keyed to the eccentric shaft 34, within certain of the cross tie members 29, are pairs of eccentrics 35. The eccentrics 35 of each pair are set 180 degrees apart and provided with eccentric straps 36 having reversely extended arms 37 pivoted at 38 to the respective pair of crossheads 32.

100 The eccentric shaft 34 is driven from an electric motor 39 mounted on the I-beam 26 at the rear of the machine and has a relatively small pulley 40 on its armature shaft aligned with a relatively large pulley 41 loose on a short transverse shaft 42 journaled in bearings on a gear case 43 formed with the intermediate pedestal 25. A belt 44 runs

over the pulleys 40 and 41. To connect the pulley 41 to the shaft 42 there is provided a yieldingly set clutch 45, such as the Fordson type, diagrammatically illustrated in Fig.

5 7. Keyed to the shaft 42, within the gear case 43, is a worm 46 which meshes with a worm gear 47 keyed to a counter-shaft 48. This counter-shaft 48 extends parallel to and under the shaft 42 and is journaled in 10 the gear cases 30 and 43 and in bearing brackets 49 on the I-beams 26. Keyed to the counter-shaft 48, within each gear case 30, is a relatively small gear 50 which meshes with a relatively large gear 51 keyed to the 15 eccentric shaft 34. Obviously, through the above described driving connections from the motor 39, the two sets of cross-heads 32, one on each side of the machine, are first moved toward each other and then from each 20 other once during each rotation of the shaft 34 by its eccentricities 35.

Automatic means manually set in motion, as will presently appear, are provided for 25 releasing the clutch 45 and holding the same released to cause the eccentric shaft 34 to make one complete rotation and then stop. This automatic means includes a substantially L-shaped lever 52 intermediately pivoted at 53 to a depending bracket on the under side of the gear case 43 with its short arm 30 extended upward into engagement with the clutch 45 and with its long arm extending horizontally under said gear case. A vertically movable plunger 54 is slidably 35 mounted at its intermediate portion in a relatively long bearing 55 on the gear case 43, and its lower end is normally held in contact with the long arm of the lever 52 by a coiled spring 56. This spring 56 encircles 40 the plunger 54 and is compressed between the bearing 55 and an adjustable abutment 57 in the form of a nut on the lower end portion of said plunger. The tension of the 45 spring 56 is such as to overcome the spring, not shown, in the clutch 45 and holds the lever 52 in a position to release the clutch 45 so that the pulley 41 is normally loose on the shaft 42.

To manually lift the plunger 54 against 50 the tension of the spring 56 and thereby release the lever 52 and permit the clutch 45 to set, there is provided a foot treadle 58 intermediately fulcrumed at 59 on the I-beams 26, with its short end engaging the long arm of the lever 52 at its under side so as to lift said arm at the time the lever 52 is operated by the foot treadle 58 which extends transversely of the machine.

To automatically lock the plunger 54 in 60 an inoperative position at the time the same is raised by the foot treadle 58, there is provided a latch plate 60 slidably mounted in a casing 61 on the gear case 43. This latch plate 60 is yieldingly projected by a spring 62 compressed between the rear end of said

latch plate and the back of the casing 61 and is provided with a round transverse aperture 63 adapted to receive a cylindrical head 64 on the upper end of the plunger 54 when the lock plate 60 is retracted and thus hold the same, as shown in Fig. 15. The latch plate 60 is also provided with a notch 65 which extends rearward from its aperture 63 to receive a reduced hub portion 66 on the lower end of the head 64 at the time the plunger 54 is lifted to prevent projecting movement of the latch plate 60. At the time the plunger 54 is lifted by the foot treadle 58, the latch plate 60 is moved by the spring 62 under the head 64 and thereby supports the same and holds the plunger 54 raised against the action of the spring 56 after the pressure on the foot treadle 58 has been released. With the plunger 54 thus held, the lever 52 is released from the action thereof so that the clutch 45 may set.

To trip the latch plate 60 out of action and thereby release the plunger 54 and permit the same to operate the lever 52 and release the clutch 45 once each half rotation of the eccentric shaft 34, there is keyed to said shaft a disk 67 having a pair of diametrically opposite cam lugs 68 on its face. Obviously, at the time one of the cam lugs 68 engages the latch plate 60 and retracts the same, the plunger 54 is released and thereby automatically operates the lever 52 which releases the clutch 45 and stops further action of the shaft 42. These cam lugs 68 are so arranged that rotation of the shaft 34 is stopped with the eccentricities holding the crossheads 32 in either of their two extreme positions.

To manually retract the latch plate 60 and thereby release the plunger 54 to permit the same to automatically operate the lever 52 and release the clutch 45 in case of an emergency, there is provided a hand lever 69 pivoted at 70 to one of the I-beams 27 and attached to the rear end of said latch plate by an eye-equipped stem 71. The shape of the eye in the stem 71 is such as to permit free movement of the latch plate 60 in one direction by the spring 62 and in the other direction by the lugs 68 without moving the lever 69.

Mounted on each sill 33 is a plurality of fixed bases 72 spaced longitudinally of the machine and having ways 73 on which squeezing abutments 74 are slidably mounted. These bases 72 are so arranged that the bases 72 on one of the sills 33 are directly opposite the bases 72 on the other sill 33, and the ways 73 of each pair are aligned. By thus arranging the bases 72, the squeezing abutments 74 are positioned in co-operating pairs with the abutments of each pair on opposite sides of the machine. The opposing faces of each pair of squeezing abutments 74 are transversely crowned at 75.

Each squeezing abutment 74 is secured to its base 72 for movement on its way 73 transversely of the machine and toward and from the other squeezing abutment 74 of the respective pair by a long transverse screw rod 76. These screw rods 76 are turnably mounted in bearings 77 on the under sides of the bases 72 and are held against endwise movement by opposing collars 78 on said rods and 10 engage opposite ends of the bearings 77. The screw rods 76 have screw-threaded engagement with depending nut-acting members 79 on the squeezing abutments 74. The outer ends of the screw rods 76 are flattened for the 15 application of a wrench by which said rods may be turned.

The screw rods 76 of each pair are axially aligned, have right and left-hand threads and are connected for common rotation but with 20 freedom for endwise movement in respect to each other by coupling sleeves 80 telescoped onto unthreaded inner end portions of said rods and held for rotation with said screw rods by pins 81 which work in longitudinally 25 extended slots 82 in said sleeves. The purpose of the sleeves 80 is to permit any one pair of screw rods 76 to be simultaneously adjusted from either side of the machine and impart reverse movements to the respective 30 pair of squeezing abutments 74 so that they may be adjusted different distances apart, for a purpose that will presently appear.

The upper surfaces of the bases 72, at the opposing faces of the squeezing abutments 74, 35 afford supports 83 for a pair of ladder side bars A. On the inner ends of each pair of bases 72 is a pair of upstanding rung supports 84 having reversely extended base portions that are slidably mounted in seats in the bases 72 and secured thereto for adjustments toward and from each other by set screws 85, which extend through slots in said base portions. In the upper ends of the rung supports 84 are V-shaped rung seats 86. It may 40 be here stated that the ladder side bars A are bored to form seats B in their opposing faces for the reduced end portions C of rungs D, as best shown in Figs. 8, 16, 17 and 21.

To longitudinally position ladder side bars 50 A for the longest ladder, for which the present machine is adapted to assemble, on the supports 83 with their rung seats B in the same vertical planes with the rung seats 86 in the rung supports 84, there is provided permanent stops 87, secured to the rear end of 55 the sills 33. For similarly positioning ladder side bars A for shorter length ladders, adjustable stops are provided, in the form of horizontal inwardly projecting pins 88 adapted to 60 be removably mounted in bore-like seats 89 formed in certain of the pairs of squeezing abutments 74, see Figs. 4, 10 and 12. These stop pins 88 are removably held in their seats 89 by spring pressed friction balls 90 that 65 extend into shallow circumferentially ex-

tended grooves 91 formed in said pins. The balls 90 are mounted in vertical bores in the respective squeezing abutments 74, normally closed by screw plugs 92. It will be noted that the bottoms of the bores in which the 70 balls 90 are mounted are contracted at their lower ends so as to prevent said balls from dropping out of said bores at the time the stop pins 88 are removed therefrom (see Fig. 12).

To center or horizontally align the rung seats B in the ladder side bars A, longitudinally positioned by either the stops 87, as shown in Fig. 3, or the stop pins 88, as shown in Figs. 4 and 12, there is provided a plurality of upper and lower jaws 93 and 94, respectively, arranged in co-operating pairs. These jaws 93 and 94 are attached by shouleder eccentric bolts 95 to certain of the squeezing abutments 74 and project horizontally inward therefrom. The inner end portions of the jaws 93 and 94 of each pair are curved toward each other and the lower jaws 94 are arranged to swing from inoperative positions below the ladder side bar supports 83 to positions above the same. The upper jaws 93 have longitudinal slots 96 through which the respective pivot bolts 95 extend and support said jaws for compound pivotal and bodily endwise movement so that they will move from inoperative positions in which they extend above the respective squeezing abutments 74 and outward of the crowned faces 75 thereof into positions in which their free ends overlie the ladder side bar supports 100 85 90 95 100 105 110 115 120 125 130 83 (see Fig. 8).

To simultaneously operate all of the pairs of jaws 93-94 on one side of the machine and impart reverse movements to the jaws of each of said pairs, there is provided a jointed rock shaft, the sections 97 of which have their ends mounted in cylindrical coupling members 98 rotatably mounted in the squeezing abutments 74 to which said jaws are attached. It will be noted by reference to Figs. 3, 4 and 5, 105 that the two pairs of jaws 93-94, on opposite squeezing abutments 74, are mounted on opposite sides thereof. It will be also be noted that the coupling members 98 are extended outward from the respective squeezing abutments 74 to which the pairs of jaws 93-94 are pivoted to afford hubs 99. Each hub 99 is provided with a pair of diametrically opposite ears 100 to which the respective pairs of jaws 93-94 are connected by 110 links 101. Set screws 102 extend into circumferentially extended channels 103 in the coupling members 98 and hold the same against endwise removal from their seats.

It will be noted that the shaft sections 97 115 are square in cross section and that the seats 104 therefor in the ends of said coupling members 98 and their hubs 99 are correspondingly formed to hold said shaft sections and coupling members for common rotation.

The sides of the seats 104 are convex in form to hold the shaft sections 97 with freedom for angular movement in respect to the coupling members 98 to permit the co-operating pair of squeezing abutment 74 to be independently adjusted toward and from each other.

At the time the rock shafts are operated to open the jaws 93 and 94, the jaws 94 will be dropped into an inoperative position under the action of gravity and the jaws 93 are lifted by the pivot pins 93' for their link connections 101 which work in cam slots 74' on the respective squeezing abutments 74, see Figs. 8 and 16.

To operate each rock shaft, there is provided a horizontal hand lever 105 pivoted at 106 to one of the squeezing abutments 74 and having a bell-crank extension 107 flexibly connected to a crank arm 108 on one section 97 of the rock shaft. Said flexible connection between the extension 107 and the crank arm 108 is in the form of a ball 109 on said arm and a slot 110 in said extension in which said ball fits for universal movement (see Fig. 13). Each lever 105 is locked with the respective pairs of jaws 93 and 94, either in their open or closed positions, by a gravity held hand lever 111 pivoted to the respective squeezing abutments 74 and having a multiplicity of longitudinally spaced ratchet teeth 112 arranged to interlock with a lock lug 113 on the lever 105.

As is well known, the lower section of an extension ladder is provided with a pair of rollers E mounted on brackets F secured to the side bars A thereof by rivets G and on which the side bars A of an upper ladder section rest when the ladder sections are connected and during the longitudinal movement of the upper ladder section in respect to the lower section. Said upper ladder section is also provided with the customary hook-acting members H pivoted at I to the side bars A of said section, and which hooks are arranged to engage any one of the rungs D on the lower ladder section to support said upper section therefrom.

To upset or head the rivets G at the time the ladder bars A are held clamped by the squeezing abutments 74, the pair of squeezing abutments 74 at the head of the machine is provided with a pair of anvil extensions 114, the faces of which are flush with the faces of the respective squeezing abutments 74 (see Fig. 5). The second pair of squeezing abutments 74 from the rear end of the machine is used as anvils for upsetting or heading the rivets G while the ladder side bars A are held clamped by the squeezing abutments 74.

By individually adjusting the squeezing abutments 74, the machine may be set to assemble a ladder having parallel side bars A, as shown in Fig. 18, or in which the side bars

A are in converging relation and have a constant taper, as shown in Fig. 19, or in which the side bars A are in converging relation at the lower portion of the ladder section and are parallel at the upper portion of said section, as shown in Fig. 20. In fact the machine may be adjusted to assemble a ladder section in which the side bars A thereof may be in various different relations.

In case it is necessary to separate the side bars A from the rungs D because of a defect in any part of the ladder section being assembled, or for any other reason, there are provided on each side of the machine a plurality of secondary abutments 115 in the form of hand levers which extend transversely of the machine and are intermediately pivoted at 116 to certain of the squeezing abutments 74 (see Figs. 3, 4 and 8). The inner or long ends of the secondary abutments 115 are in the form of heavy upturned hooks, and which abutments are gravity held with said hooks materially below the side bar support 83 where they are out of the way. By depressing the outer ends of the secondary abutments 115 their hook ends are raised into positions between certain of the rungs D in which they closely engage the inner faces of the side bars A at the transverse centers thereof, as shown by broken lines in Fig. 8. While the secondary abutments 115 are thus held, the machine may be operated to open the squeezing abutments 74 and thereby cause the side bars A to engage said secondary abutments and be carried thereby laterally outward with the squeezing abutments 74 and stripped from said rungs.

By positioning all of the secondary abutments 115 in operative positions, the entire ladder section may be disassembled or any part of the ladder section may be disassembled by operating only certain of the secondary abutments 115, for instance, when it is necessary to remove only a single rung.

The operation of the extension ladder assembling machine may be briefly described as follows:

It may be assumed that there is an attendant on each side of the machine and that the motor 39 is driving the pulley 41, which is normally loose on the shaft 42, so that the driving connections to the eccentric shaft 34 are idle. It also may be assumed that the two rows of crossheads 32 are separate and hence the squeezing abutments 74 are open as well as the jaws 93 and 94. It is, of course, understood that the squeezing abutments 74 of each pair are properly spaced for the type of ladder to be assembled in the machine.

The attendants first place a pair of ladder side bars A, that have been bored to form the rung seats B, on the supports 83 with the outer faces of said bars against the crowned faces 75 of said squeezing abutments, thus bringing the rung seats B in said side bars

- in opposing relation. At the time the ladder side bars A are placed on their supports 83, they are longitudinally positioned either by the stops 87 or the stop pins 88, depending on the length of the ladder section being assembled, to position the rung seats B in the same vertical planes with the rung seats 86 in the rung supports 84. After the ladder side bars A have been properly positioned 5 the length of the ladder section being assembled, to position the rung seats B in the same vertical planes with the rung seats 86 in the rung supports 84. After the ladder side bars A have been properly positioned 10 on the supports 83 the attendants manipulate the levers 105 to operate the rock shafts 97 and thereby close the jaws 93 and 94 onto said side bars. This closing action of the jaws 93 and 94 lift the ladder side bars A 15 from their supports 83 and transversely center their rung seats B with the rung seats 86 in the rung supports 84 and also rigidly hold said ladder side bars A. At the limit of the movement of the levers 105 to close the jaws 20 93 and 94, the latch levers 111 automatically hold said levers 105 where set so that the attendant may release the same. 25 The rungs D are then placed in the seats 86 in the rung supports 84. If the machine 30 is adjusted to assemble a ladder section in which the side bars A are parallel, the rungs D, of course, will be all of the same length. If the type of ladder is such that the side bars A are varying distances apart, the rungs, of 35 course, will have to be of the proper length and properly arranged on the supports 84. One of the attendants then steps on the foot treadle 58 to rock the lever 52 and thereby release the clutch 45 to permit said clutch to 40 automatically set and complete the operating connections to the eccentric shaft 34. At the same time the foot lever 58 is depressed, the plunger 54 is raised by the lever 52 against the action of the spring 56 and lifts its cylindrical head 64 from its seat 63 and thereby 45 permits the spring 62 to project the latch plate 60 in the path of movement of the cam lugs 68. This movement of the latch plate 60 positions the same under the head 64 and thereby automatically locks the plunger 54 50 raised so that the attendant may release the depressed foot treadle 58. The spring action of the clutch 45 is such as to overcome the lever 52 and hold the same as positioned by 55 the treadle 58. Under the rotation of the shaft 34 its eccentrics 35, acting through their straps 36 and arm 37, draw the two rows of crossheads 32 toward each other and thereby operate and close the squeezing abutments 74 and cause the same to move the ladder side bars A toward each other and force the reduced ends C, of the rungs D, into the rung seats B with the ends of the rungs D tightly pressed against the inner faces of the 60 ladder side bars A. During this movement of the squeezing abutments 74, the shaft 34 has made a one-half rotation, or in other words, its eccentrics 35 have moved 180 degrees, and at the limit of this movement the 65 cam lug 68, diametrically opposite the latch plate 60 at the time the machine is started, is moved 180 degrees and engages said latch plate 60 and forces the same back against the tension of the spring 62 and aligns its seats 63 with the head 64 and thereby permits the compressed spring 56 to move the plunger 54 downward and operate the lever 52 to release the clutch 45 and stop further driving action to the shaft 34. At the time the plunger 54 is depressed, the movement 70 of the lever 52 resets or lifts the foot treadle 58. After the side bars A and rungs D are assembled, the levers 105 are manipulated to open the jaws 93 and 94 so that the side bars A and rungs D may be permanently connected by nails J driven into said side bars and the reduced ends C of the rungs D, as shown in Figs. 16 and 21. The purpose of mounting the jaws 93 for endwise as well as pivotal movement is to cause the same to move outward from the side bars A so that the nails J may be driven, without danger of striking said jaws 93. 75
- In case the brackets F or the hooks H are to be secured to a ladder section, their rivets are upset respectively against the anvil extension 114 or the respective squeezing abutments 74 while said ladder section is held by the squeezing abutments 74. 80
- At the completion of the nailing of the side bars A to the rungs D, one of the attendants steps on the foot treadle 58 to start the driving connections to cause the eccentrics 35 to make another one-half rotation and return the crossheads 32 to their original or separated 85 positions and thereby open the squeezing abutment 74 and release the completed ladder section so that the same may be removed from the machine. The action of the machine in releasing a completed ladder section is identical with that in closing the squeezing abutments 74 with the exception that the crosshead 32 and parts carried thereby are given reverse movements. 90
- At the completion of the nailing of the side bars A to the rungs D, one of the attendants steps on the foot treadle 58 to start the driving connections to cause the eccentrics 35 to make another one-half rotation and return the crossheads 32 to their original or separated 95 positions and thereby open the squeezing abutment 74 and release the completed ladder section so that the same may be removed from the machine. The action of the machine in releasing a completed ladder section is identical with that in closing the squeezing abutments 74 with the exception that the crosshead 32 and parts carried thereby are given reverse movements. 100
- What I claim is: 110
1. In an extension ladder assembling machine, two rows of squeezing abutments, operating means for moving at least one row of said abutments alternately toward and from the other row thereof, rung supports between the two rows of squeezing abutments, and automatic means for transversely centering a pair of ladder side bars in respect to the rung supports. 115
  2. In an extension ladder assembling machine, two rows of squeezing abutments, operating means for moving at least one row of said abutments alternately toward and from the other row thereof, rung supports between the two rows of squeezing abutments, supports at the opposing faces of the squeezing abutments for ladder side bars having rung seats, means for longitudinally positioning said bars on the supports therefor with their rung seats aligned in one direction 120
  3. In an extension ladder assembling machine, two rows of squeezing abutments, operating means for moving at least one row of said abutments alternately toward and from the other row thereof, rung supports between the two rows of squeezing abutments, supports at the opposing faces of the squeezing abutments for ladder side bars having rung seats, means for longitudinally positioning said bars on the supports therefor with their rung seats aligned in one direction 125
  4. In an extension ladder assembling machine, two rows of squeezing abutments, operating means for moving at least one row of said abutments alternately toward and from the other row thereof, rung supports between the two rows of squeezing abutments, supports at the opposing faces of the squeezing abutments for ladder side bars having rung seats, means for longitudinally positioning said bars on the supports therefor with their rung seats aligned in one direction 130

with the rung supports, and automatic means for lifting said bars from their supports and transversely positioning the same with their rung seats aligned with the rung supports in the other direction.

3. In an extension ladder assembling machine, two rows of squeezing abutments, operating means for moving at least one row of said abutments alternately toward and from the other row thereof, rung supports between the two rows of squeezing abutments, co-operating pairs of jaws for automatically transversely positioning a pair of ladder side bars in respect to the rung supports, and operating means for the jaws.

4. In an extension ladder assembling machine, two rows of squeezing abutments, operating means for moving at least one row of said abutments alternately toward and from the other row thereof, rung supports between the two rows of squeezing abutments, ladder side bar supports at the opposing faces of said abutments, co-operating pairs of jaws arranged to lift ladder side bars from said supports and automatically transversely position the same in respect to the rung supports, and operating means for the jaws.

5. In an extension ladder assembling machine, two rows of squeezing abutments, operating means for moving at least one row of said abutments alternately toward and from the other row thereof, rung supports between the two rows of squeezing abutments, co-operating pairs of jaws for automatically transversely positioning a pair of ladder side bars in respect to the rung supports, and operating means for the jaws, said jaws being arranged to permit ladder side bars held thereby to be moved laterally against the opposing faces of said abutments.

6. In an extension ladder assembling machine, two rows of squeezing abutments, operating means for moving at least one row of said abutments alternately toward and from the other row thereof, rung supports between the two rows of squeezing abutments, co-operating pairs of jaws for automatically transversely positioning a pair of ladder side bars in respect to the rung supports, and movable secondary abutments arranged to be set in position to be engaged by ladder side bars held by said jaws and separate said bars by a movement of one row of said abutments away from the other row thereof.

55 7. In an extension ladder assembling machine, two rows of bases arranged in opposite pairs, squeezing abutments mounted on said bases, rung supports between said two rows of squeezing abutments, means for individually adjusting each pair of co-operating squeezing abutments to set the same different distances apart, and means for moving at least one row of said bases alternately toward or from the other row thereof.

8. The structure defined in claim 6 in which the operating means for said pairs of abutments may be manipulated from either side of the machine.

9. In an extension ladder assembling machine, two rows of squeezing abutments, operating means for moving at least one row of said abutments alternately toward and from the other row thereof, rung supports between the two rows of squeezing abutments, co-operating pairs of pivoted jaws for automatically transversely positioning a pair of ladder side bars in respect to the rung supports, and crank-acting means for imparting reverse movements to the jaws of each pair.

10. The structure defined in claim 8 in which the jaws of each pair are individually mounted on eccentric pivot studs.

11. The structure defined in claim 6 in further combination with co-operating pairs of jaws for automatically transversely positioning a pair of ladder side bars in respect to the rung supports, and operating means for simultaneously operating the pairs of jaws at each side of the machine and for imparting reverse movements to the jaws of each pair including flexibly connected shaft sections.

12. In an extension ladder assembling machine, two rows of squeezing abutments, operating means for moving at least one row of said abutments alternately toward and from the other row thereof, ladder side bar supports at the opposing faces of said abutments, rung supports between said ladder side bar supports, upper and lower pairs of jaws arranged in co-operating pairs for automatically transversely positioning a pair of ladder side bars on the supports therefor in respect to the rung supports, said upper jaws being mounted for compound pivotal and bodily shifting movements in respect to the supports for the ladder side bars, and means for simultaneously operating the pairs of jaws at each side of the machine and imparting reverse movements to jaws of each pair.

13. In an extension ladder assembling machine, a pair of longitudinally extended sills, crossheads supporting at least one of said sills for lateral movement toward and from the other thereof, a driven shaft, connections including eccentrics on said shaft for operating the crossheads, opposite pairs of bases mounted on the sills, co-operating pairs of squeezing abutments mounted on the bases, rung supports between the squeezing abutments of said pairs, and means for individually adjusting each pair of co-operating squeezing abutments to set the same different distances apart.

14. In an extension ladder assembling machine, two squeezing abutments, operating means for moving at least one of said abutments alternately toward and from the other

thereof, a rung support between the abutments, and operating means having members for automatically transversely centering a pair of ladder side bars in respect to the rung support.

15. The structure defined in claim 14 in which the abutments are crowned longitudinally in respect to the ladder side bars and in which the vertexes of the crowns are 10 aligned with the rung support.

16. In an extension ladder assembling machine, two squeezing abutments, operating

means for moving at least one of said abutments toward and from the other thereof, a rung support between the abutments, means 15 for longitudinally positioning a pair of ladder side bars having a pair of rung seats to align said seats in one direction with the rung support, and automatic means for transversely positioning the ladder side bars to 20 align the rung seats in the other direction with the rung support.

In testimony whereof I affix my signature.
JOHN E. KALGREN.
